Primary Examiner—Antoine Duval Davis**[57] CLAIM**

The ornamental design for a drill bit finger, as shown and described.

DESCRIPTION

FIG. 1 is a right side view in elevation of a drill bit finger (without cutting head attached) showing our new design; FIG. 2 is a rear view thereof in elevation (without cutting head attached);

FIG. 3 is a perspective view thereof from the rear (without cutting head attached);

FIG. 4 is a front view thereof in elevation (without cutting head attached);

FIG. 5 is a left side view thereof in elevation (without cutting head attached);

FIG. 6 is a bottom view thereof in plan (without cutting head attached);

FIG. 7 is a perspective view thereof from the front (without cutting head attached);

FIG. 8 is a front view in elevation of the drill bit finger (with cutting head attached) showing our new design;

FIG. 9 is a left side view thereof (with cutting head attached);

FIG. 10 is a perspective view thereof from the front (with cutting head attached);

FIG. 11 is a top view thereof in plan (with cutting head attached);

FIG. 12 is a top view thereof in plan (with cutting head attached);

FIG. 13 is a right side view thereof in elevation (with cutting head attached);

FIG. 14 is a rear view thereof in elevation (with cutting head attached); and,

FIG. 15 is a perspective view thereof from the rear (with cutting head attached).
